UNITED STATES PATENT OFFICE.

WILLIAM C. CROSS, OF BOSTON, MASSACHUSETTS.

BAG-MACHINE.

SPECIFICATION forming part of Letters Patent No. 243,857, dated July 5, 1881.

Application filed May 17, 1881. (No model.)

To all whom it may concern:

Be it known that I, WILLIAM C. CROSS, of Boston, Massachusetts, have invented certain new and useful Improvements in Machinery for Making Paper Bags, of which the following is a specification.

My invention relates to machines for making satchel-bottom paper bags. It refers particularly to that portion of the machine by which the second and the final folds are made; and it consists in the combination and arrangement, substantially as hereinafter described, of two pairs of continuously-rotating folding-rolls, one roll of each pair carrying a clamping-jaw and the other carrying a blade, which tucks the blank along the line of fold down into the bite of the jaw, whereby, without the intervention of other active instrumentalities, I am enabled to make the last two folds of the satchel-bottom.

The nature of my invention and the manner in which the same is or may be carried into effect can best be explained and understood by reference to the accompanying drawings, in which—

Figure 1 is a diagrammatic side elevation of so much of a paper-bag machine as is needed to illustrate my invention. Figs. 2 and 3 are like sections, representing the parts in the different positions which they assume during the making of the folds which complete the satchel-bottom. Fig. 4 is an end elevation of the machine. Fig. 5 is an elevation of one of the clamp-rolls on an enlarged scale, representing spring-lifters, which may be employed to raise from the recess in the roll that portion of the blank which is taken hold of by the clamping-jaw. Fig. 6 is a transverse section of said roll. Fig. 7 is a perspective view of a portion of one of the clamping-rolls. Figs. 8 and 9 are views on an exaggerated scale, intended to represent the folds formed by the action of the folding mechanism. Fig. 10 is a view of one of the cam-holding brackets.

I have not deemed it necessary to show the gearing by which the rolls are driven; that as well as the supporting-frame may be of any approved construction. Nor have I deemed it necessary to represent the mechanism for making and pasting and severing the paper tube

and for forming the diamond fold on the successive blanks.

The diamond-fold-forming mechanism which I prefer and in practice employ is that shown and described in my Letters Patent No. 221,531, 55 of November 11, 1879, to which reference may be made. From the delivery-rolls of that mechanism the diamond-folded blank, with diamond fold uppermost and in front, passes to the paste-rolls of the mechanism which I shall now 60 proceed to describe.

The paste-rolls referred to are indicated by the letters A.B. The upper roll, A, has paste-ridges formed on it of the kind shown in my Letters Patent No. 239,457, of March 29, 1881, 65 and in Stocking's Letters Patent No. 222,544, of December 9, 1879, said ridges being supplied with paste by suitable means, as indicated in said Letters Patent, and acting to deposit parallel lines of paste upon the diamond 70 fold in the usual way.

In advance of the paste-rolls is the first pair of folding-rolls, consisting of the clamping-jaw-carrying roll C and the blade-carrying roll D. In a peripheral recess, c, formed in and longitudinally of roll C is the vibratory clamping-jaw a, which moves to and from the side b of the recess c, (b constituting, in effect, a stationary clamping surface or jaw, against which the jaw a clamps that part of the blank 80 tucked down between them.) The jaw c is mounted on a rock-shaft, d, supported in proper bearings in the roll C, and projecting at one end beyond the end of the roll. On this projecting end of the shaft is fixed a crank-arm, 85 e, which, during the revolution of the roll, is brought in contact with and acted on by a cam, f, attached to a bracket, g, fixed to the main frame. The cam is preferably adjustably connected to the bracket, in order that its position 90 may be varied so as to vary the point at which the jaw opens and closes, and for this purpose is, in the present instance, attached to the bracket by holding-bolts or set-screws, which enter slots formed in the bracket, as indicated 95 in Fig. 10. All of the various cams which act on the blades and jaws are secured in this manner to the frame, so that a description of one will answer for all. A spring, h, Fig. 7, encircling the rock-shaft, and secured at one end 100

thereto and at the other end to the roll, serves to throw the jaw in the opposite direction from that in which it is moved by the cam. The jaw is opened by the cam, and, when released 5 from the control of the latter, is closed by the spring.

In the roll D is mounted the blade *i*, which tucks the blank along the proper line of fold down into the bite of the clamping-jaw in the 10 roll C below. This blade is supported in a radial recess formed longitudinally of the roll D, and is preferably movable back and forth therein. It is pressed forward by a spring, *j*, and is retracted against the stress of the spring 15 by cams *k* acting on its laterally-projecting studs *k*². The parts are so arranged and their movements are so timed relatively to the movement of the diamond-folded blank *w* that the jaw and blade are brought opposite one another 20 just as the front flap or point, *x*, of the diamond has passed the proper distance between the rolls C D, so that the blade will tuck this part of the blank along the proper line of fold, 1, Figs. 8 and 9, into the bite of the 25 vibratory jaw, which is about clearing its cam. Further rotary movement of the rolls clears the jaw of its cam, allowing it to close on the part of the blank tucked between it and the stationary clamping-surface *b*, after which the blade is re- 30 tracted by its cam, the jaw presses and creases the blank along the line of fold, and then, by the action of its cam, is opened so as to release the blank in time to allow the latter to pass, with its front flap creased and partly bent or 35 folded back, as indicated in Fig. 3, over the table E to the second pair of folding-rolls, F G.

The flap *x* is turned back and down along the line 1 as it passes between the rolls F G, 40 which press the fold down, and it may be found desirable in practice to employ a stationary cross plate or bar, H, which will wipe back the flap *x* as it passes beneath it, as indicated in dotted lines in Fig. 3, so as to insure that 45 the blank shall enter properly between the said rolls F G. The rolls F G are provided, the one with a vibratory jaw, *l*, and the other with a blade, *m*, which in construction and arrangement are similar to those already de- 50 scribed with reference to rolls C D, and are in like manner combined with springs and with controlling-cams *n o*. The cam *n*, how- ever, is made of such length as to permit the jaw *l* to retain its hold upon the blank for 55 a longer time than does the first jaw, *a*, this being essential in order that the folded end of the blank may be carried around under and beyond the presser roll or bar I, which may be an idle-roll or a stationary bar, as preferred. 60 The jaw *l* and blade *m* are so positioned and the movement of their rolls F G is so timed with relation to the blank that the jaw and blade come opposite one another at the time when the blank has passed between the rolls 65 far enough to bring the rear flap, *y*, of the dia- mond fold between them on the line 2 of the

final fold. The blade tucks the flap *y* along this line down into the bite of the jaw, tucking down also along with the flap the underlying body of the blank, in which a blind fold 70 is consequently formed, as indicated in Figs. 2 and 3 and by the line 3 in Figs. 8 and 9. The jaw *l* retains its hold upon the blank and draws it along under the pressure roll or bar I, which wipes and folds back upon the portion 75 of the blank in rear of line 3 that portion in front of said line, as indicated in Fig. 3, pressing down the folds *x y*, and thus virtually completing the satchel-bottom. After the bag passes the presser-roll I the jaw releases 80 its hold and the bag drops upon the drier, or apron which conveys it to the drier, where it is straightened out, and where, if desired, it can be pressed.

I have shown in Figs. 1, 2, and 3 the rolls 85 of each pair as separated somewhat from one another. This has been done in order not to obscure the drawings. In practice the rolls of each pair revolve in yielding contact with one another, all being so geared as to move at 90 the same peripheral speed.

It may be found desirable under some circumstances to employ some means whereby, when the jaws release their hold, the part of the blank grasped by them shall be lifted out 95 of the recess in which it has been clamped. To this end I make use of light spring-strips *p*, which are seated in slots in the jaw-rolls, as indicated in Figs. 5 and 6, and extend across the jaw, in which latter, at the points where 100 the spring-lifters cross it, are formed notches, so that when the blade descends it can de- press the spring-lifters into their seats below the acting face or part of the jaw, as indicated by dotted lines in Fig. 6. When, under these 105 circumstances, the jaw releases its hold on the blank, the spring-lifters below are free to rise, and in so doing throw the blank out of the re- cess *c*.

In conclusion, I remark that I am aware 110 that it is not new, broadly considered, to use a pair of clamping-jaw and blade carrying rolls for making each of the final folds of a satchel-bottom paper bag. This is shown in Letters Patent Nos. 222,544 and 239,457, hereinbefore 115 referred to; but in both of said patented machines there is between the two pairs of rolls intermediate mechanism, by which the points of the diamond fold are reversed, and the blank in this condition delivered from the one set of 120 rolls to the other. In my present arrangement, however, the point-reversing mechanism, as well as all mechanism for taking the blank from one and transferring it to the next set of rolls, is dispensed with, and the folding de- 125 vices are so arranged and timed with reference to one another that the blank can pass with its folded flap in front directly from the bite of the first pair of rolls into the bite of the second, the blind fold formed by the ac- 130 tion of the latter being easily straightened out afterward. Therefore

What I claim as my invention is—
The combination of two pairs of clamping-
jaw and blade carrying rolls and means for di-
recting the blank with the folded end of the
diamond foremost from the first to the second
pair of rolls, the parts being arranged and op-
erating substantially as hereinbefore set forth.

In testimony whereof I have hereunto set
my hand this 10th day of May, A. D. 1881.

WILLIAM C. CROSS.
